UNITED STATES PATENT OFFICE.

WILLIAM H. WALTON, OF BROOKLYN, NEW YORK, ASSIGNOR, BY DIRECT AND MESNE ASSIGNMENTS, TO WALTON SIGNAL COMPANY, OF NEW YORK, N. Y., A CORPORATION OF NEW YORK.

RAILWAY-SIGNAL.

SPECIFICATION forming part of Letters Patent No. 715,183, dated December 2, 1902.

Application filed May 31, 1902. Serial No. 109,769. (No model.)

To all whom it may concern:

Be it known that I, WILLIAM HENRY WALTON, a citizen of the United States, residing in Brooklyn, in the county of Kings and State 5 of New York, have invented certain new and useful Improvements in Railway-Signals, of which the following is a specification.

My invention is particularly designed for electric railways or other railways operating 10 single cars; but it is also capable of application to railways having trains of cars. It is also especially intended and is described hereinafter as applied to a tunnel-road or to the tunnel-section of such a road, but may be 15 also used on other parts of a railway system.

The object of the invention is to enable a car to block the section or portion of track immediately behind it automatically and without the use of mechanical signal-operating 20 devices.

To this end my invention consists in arranging fixed signal-lamps in such relation to the track or tracks as to be obscured or hidden by the car itself from an immediately succeeding car. Preferably the form of signal 25 adopted has screens so arranged as to permit the light to be observable only from the direction of approach of trains and to hide the light in the other direction, so that where double tracks are used the light of one track will not confuse the motorman or engineer whose 30 vehicle is on the adjacent track.

In the accompanying drawings, Figure 1 is a plan view of a double-track tunnel-road to 35 which my invention is applied. Fig. 2 is a longitudinal sectional elevation thereof. Fig. 3 is a transverse sectional elevation of one track of such road to a larger scale. Fig. 4 is a longitudinal sectional elevation, to the 40 same scale as Fig. 3, of a single signal and adjacent devices.

The tunnel-walls are represented at 1 and the tracks at 2. Located between the rails of the track are fixed or immovable signal- 45 lamps 3, which are maintained constantly lighted and have a reflector 4 so arranged in relation thereto as to throw their light only toward the oncoming cars of the track in which such signal is placed. The lamps may 50 be electric, as shown, and lighted from any

convenient source of electricity or may be oil or gas lamps, as is most convenient. As shown in Figs. 3 and 4, the reflector or shield 4 affords a supporting and containing case or box for the lamp and is fastened upon the cross-tie of the track or separate foundations. The distance between the lights will depend on local conditions and on the speed of movement of the cars. I have shown in Fig. 1 an arrangement of three of these lights on one 55 track and two on an adjacent track at somewhat more than a car's length apart. This is, however, for purpose of illustration only, as the lights would preferably be arranged at considerably greater distances apart. In operating the rules may require one or more of these lights to appear between the car 5 and the next car 6 in front thereof. It will be noticed that at the right hand of Fig. 1 the car 6 is immediately over one of the signals and 60 will hide it entirely from the car 5, so that the motorman on the latter will see only a single signal, and it is believed to be the best condition of operation to have at least one signal-light showing between the cars. 75

In addition to the arrangement of a signal between the rails the signal 4^a may be arranged alongside of the track, either adjacent to the several signals 4 or interspaced therewith. The signals 4^a, if so arranged, will, as shown at the right hand of Fig. 1, be so close to the car as to be hidden from a succeeding car when the car 6 is passing. The lights 4^a are, as will be noticed, arranged at the left-hand side of the track, which in case of a 85 double-track road, such as shown in Fig. 1, will bring all of them between the tracks. For daylight use the inner surface of the reflector 4 may be under some conditions and if painted an appropriate color—red, for instance—serve as a sufficient signal device should the lamps 3 be extinguished. 90

It will be observed that the form of signal device herein described is not dependent for the proper fulfilment of its function upon 95 the operation of any movable mechanical devices and is simple and always in order; also, that either of the arrangements herein shown and described or any equivalent thereof for placing the signals in such relation to the 100

track that they will be obscured by a passing car from the following car is intended to be covered by the broader statements of claims hereinafter made.

5 Having thus described my invention, the following is what I claim as new therein and desire to secure by Letters Patent:

1. A railway-signal, having arranged in juxtaposition to the tracks a fixed signal device or devices arranged so as to be hidden by the car or train from succeeding cars or trains.

2. In a railway-signal, in combination with a track or tracks, signal devices arranged so as to be hidden by a passing car or train from

a succeeding car or train and having deflectors 15 arranged to obscure the signal devices in one direction.

3. In a railway-signal, in combination with a track, a fixed signal device or devices arranged between the rails thereof and projecting into view of an approaching car but arranged to be hidden by a car or train from a succeeding car or train on such track.

WILLIAM H. WALTON.
